GUM TAPE APPLIER

William C. Renne, Jr., Kansas City, Mo.

Application January 7, 1947, Serial No. 720,666

9 Claims. (Cl. 216—29)

1

This invention relates to new and useful improvements in a gummed tape applier, and has particular reference to a portable, hand operable gummed tape applier.

The principal object of the present invention is the provision of a hand operable gummed tape applier whereby gummed tape contained on a roll within said applier is pulled from said roll, moistened, applied to a package or other surface under pressure, and cut off at any desired length.

Another object is the provision of a gummed tape applier adapted to be used in any desired position, and to apply tape even to vertical or overhead surfaces.

Further objects are economy and ruggedness of construction, and simplicity and dependability of operation.

With these objects in view, as well as further objects which will become apparent during the course of the specification, reference will be had to the drawings, wherein:

Figure 1 is a side elevation of a gummed tape applier in operative relationship to a package, shown in the tape applying position in solid lines and in the tape cutting position in dotted lines.

Fig. 2 is a vertical mid-section of the tape applier shown in Figure 1.

Fig. 3 is a sectional view taken on line III—III of Figure 2.

Fig. 4 is a fragmentary vertical section taken on line IV—IV of Figure 2.

Fig. 5 is a fragmentary horizontal section taken on line V—V of Figure 4.

Fig. 6 is an enlarged fragmentary vertical section taken on line VI—VI of Figure 1.

Fig. 7 is an enlarged fragmentary side elevation of the forward portion of the reservoir handle, detached from the applier frame.

Fig. 8 is a vertical section taken on line VIII—VIII of Figure 7.

Like reference numerals apply to similar parts throughout the several views, and the numeral 10 applies to a frame comprising a single piece of sheet metal bent to form two spaced apart side walls 12 joined by a connecting portion 14 at the upper edge thereof.

A shaft 16 extends between and is rotatably carried by side walls 12 adjacent the forward edges thereof, and a pressure wheel 18 is rigidly mounted on said shaft between said side walls. The rim 20 of said wheel is of greater width than the gummed tape to be applied, and carries a tire 22 of rubber or other soft, resilient material. Said tire is crowned slightly in order that tape passing around said wheel will seek center.

2

A shaft 24 extends between side walls 12 and fixed thereto adjacent the rearward edges thereof, carries for rotation a moistening roller 26. Said roller comprises a hub 28, a plurality of spaced stiffener discs 30 rigidly fixed to said hub, and a quantity of wicking 32, or similar material, filling the space between said discs and extending outwardly past the edges of said discs. Roller 26 is positioned to engage wheel 18 with a light pressure.

Two spool support arms 34, clamped at their lower ends to side walls 12 at the upper edges thereof by means of bolt 36, extend upwardly therefrom. An axle 38 extends between and is supported by the upper ends of said support arms, said axle being adapted to pass through the hub 40 of a spool 42 of gummed paper tape. Said spool is centered on said axle by a spacer washer 44 and friction disc 46, said washer and disc being carried on said axle on opposite sides of spool 42, as shown in Figure 6. Said friction disc is compressed between hub 40 and a support arm 34, and serves to maintain a tension in the tape as it is unrolled from said spool.

From said spool, tape 50 is passed through a centering guide 48 carried on bolt 36. Said guide, as shown in Figures 4 and 5, comprises a U-shaped member of a slightly greater width than tape 50. Bolt 36 passes through the legs of said guide, and said guide is centered longitudinally on said bolt by means of a pair of spacer bushings 52.

A U-shaped blade support 54, the forwardly extending legs of which are pivotally attached to side walls 12 adjacent the lower forward corners thereof, carries at its rearward edge a centrally mounted blade 56, said blade extending upwardly and having at its upper edge a notched cutting edge 58 parallel to the shaft 16 of wheel 18. Said blade is adapted by the pivotal movement of support 54 to be moved into contact with wheel 18 at a point just below the point of contact between wheel 18 and roller 26. Notches 60 are cut in the lower edges of side walls 12 to permit free movement of blade support 54. The pivoting arc of said blade away from wheel 18 is limited by stops 62, cut from the forward edges of side walls 12 and bent outwardly to extend above and limit the upward movement of the extended forward ends of blade support 54.

A reservoir handle 64 is removably attached to frame 10 by means of screw 66 and bolt 68, and extends rearwardly from said frame. Said handle comprises a body portion 70 enclosing a water chamber 72, said body portion being ex-

ternally shaped to provide a convenient grip for the operator, and a cup portion 14 extending forwardly from said body portion and encircling substantially the lower half of moistening roller 26. The forward lip 16 of said cup is adapted to contact and to compress slightly the wicking 32 of said roller, as shown in Figure 2. Said cup contains a pad 18 of a porous material adapted to absorb and retain water readily. Said pad is formed to fill said cup and to contact roller 26 about approximately half of its circumference. A single hole 80 through the forward wall of handle body 70 at the lower edge thereof, connects water chamber 72 with cup 14. Handle 64 is provided at its rearward end with a filling plug 82, and a gasket 84 provides a water-tight seal between said plug and said handle.

The operation of the tape applier is substantially as follows. Plug 82 is removed and chamber 72 partially filled with water. Water runs from said chamber through hole 80 and moistens pad 18 contained in cup 14. This flow is controlled by vacuum. When the pores of the pad are filled with water, a vacuum will form over the water in chamber 72 and the flow will cease. When the water in the pad is used or evaporates, air will be allowed to enter chamber 72 through hole 80, relieving said vacuum and allowing more water to flow. Wicking 32 being in contact with said pad, will absorb water therefrom and become moist throughout.

A roll of gummed tape 42 rolled with the adhesive on the outside is mounted on axle 38. The end 50 of the tape is threaded through guide 48, which feeds said tape on to the center of wheel 18. The tape then passes between wheel 18 and moistening roller 26, whereby the adhesive of said tape is moistened. Since the wicking 32 of said roller bulges slightly over lip 16 of cup 14, the end of the tape is prevented from entering between said roller and said lip. The tape is then passed around wheel 18 to a point where said wheel is pressed against a package 66 or other surface, the tape there being applied under pressure to said package.

In applying the tape the applier is held in the position shown in solid lines in Figure 1, and is pulled to the rear. When the desired length of tape has been applied, handle 64 is lowered to the position shown in dotted lines in Figure 1, and twisted about a vertical axis, said lowering and twisting being accomplished in a single movement without interrupting the backward pull. Blade support 54 is thus brought into contact with the surface to which tape is being applied, thereby pivoting said blade support upwardly and forcing blade 56 into contact with the tape at a point just below the point of contact of wheel 18 and roller 26. The continued rearward movement of the applier will cause the tape to be cut or torn along the edge 58 of said blade. The unused moistened end of the tape is thus very short, and furthermore, since this end is contained within frame 10, it can not accidentally contact and stick to other articles when the applier is laid aside. And, since the moistening roller is moist at all times, the tape cannot stick to said roller between uses of the applier.

Since the water in handle 64 is enclosed, and since pad 18 will hold sufficient water for considerable usage, it is apparent that the applier may be used on any surface, even vertical or overhead surfaces. And, even though spool 42 is

shown in the drawings with the tape rolled thereon with the adhesive side out, the applier can be adapted to use spools of tape rolled with the adhesive side in, by simply reversing said spool on axle 38.

The improvements I claim and desire to protect by Letters Patent are:

1. A gummed tape applier comprising a frame, a roll of tape carried by said frame, a pressure wheel rotatably carried by said frame whereby tape drawn from said roll is applied to any surface on which said wheel is rolled, a moistening roller rotatably carried by said frame engaging said pressure wheel and adapted to be driven thereby, whereby the gummed side of said tape is moistened, a water reservoir carried by said frame, means for controlling the flow of water from said reservoir to said moistening roller, and a handle for said frame whereby said pressure wheel may be manually pressed against the surface to which the tape is being applied.

2. A gummed tape applier comprising a frame adapted to carry a roll of gummed tape for rotation, a pressure wheel rotatably carried by said frame, a resilient tire carried by said wheel whereby tape drawn from said roll is applied under pressure to any surface along which said wheel is rolled, said tire being crowned thereby causing the tape passing around said tire to seek the center thereof, a moistening roller rotatably carried by said frame and engaging said resilient tire, whereby the gummed side of said tape is moistened, a water reservoir carried by said frame, means for controlling the flow of water from said reservoir to said moistening roller, and a handle for said frame whereby said pressure wheel may be manually pressed against a surface to which tape is to be applied.

3. A gummed tape applier comprising a frame adapted to carry a roll of gummed tape, a pressure wheel rotatably carried by said frame whereby tape drawn from said roll is applied under pressure to any surface with which said wheel is rolled in contact, a guide carried by said frame whereby said tape is guided on to the center of said pressure wheel, a moistening roller rotatably carried by said frame, engaging said pressure wheel and adapted to be driven thereby, whereby the gummed side of said tape is moistened, a water reservoir carried by said frame, means for controlling the flow of water from said reservoir to said moistening roller, and handle for said frame whereby said pressure wheel may be manually pressed against the surface to which tape is being applied.

4. A gummed tape applier comprising a frame adapted to receive a roll of gummed tape, a pressure wheel rotatably carried by said frame, a resilient tire carried on said wheel whereby tape drawn from said roll is applied to any surface with which said wheel is rolled in contact, said tire being crowned, thereby causing the tape passing around said tire to seek the center thereof, a guide carried by said frame whereby said tape is guided onto the center of said resilient wheel, a moistening roller rotatably carried by said frame, and engaging said resilient tire, whereby the gummed side of said tape is moistened, a water reservoir carried by said frame, means for controlling the flow of water from said reservoir to said moistening roller, and a handle for said frame whereby said pressure wheel may be manually pressed against the surface to which tape is being applied.

5. A gummed tape applier comprising a frame adapted to carry a roll of gummed tape, a pressure wheel rotatably carried by said frame whereby tape is drawn from said roll and applied under pressure to any surface with which said pressure wheel is rolled in contact, a moistening roller rotatably carried by said frame, engaging said pressure wheel and adapted to be driven thereby, a handle portion carried by said frame, said handle portion comprising a water reservoir having a sealable filling opening and a cup portion extending beneath and partially encircling said moistening roller, and a resilient porous pad contained in said cup and formed to contact a portion of the periphery of said moistening roller, said pad receiving water from said reservoir through an opening provided in the forward wall of said reservoir adjacent the bottom of said cup.

6. A gummed tape applier comprising a frame adapted to carry a roll of gummed tape, a pressure wheel rotatably carried by said frame, whereby tape is drawn from said roll and applied under pressure to any surface on which said pressure wheel is rolled, a moistening roller of porous absorbent material rotatably carried by said frame and operatively engaging said pressure wheel, a handle portion carried by said frame, said handle portion comprising a water reservoir having a sealable filling opening and a cup portion extending beneath and partially encircling said moistening roller, and a resilient porous pad contained in said cup and formed to contact a portion of the periphery of said moistening roller, said pad receiving water from said reservoir through an opening provided in the forward wall of said reservoir adjacent the bottom of said cup.

7. A gummed tape applier comprising a frame adapted to carry a roll of gummed tape, a pressure wheel rotatably carried by said frame whereby tape drawn from said roll is applied under pressure to any surface on which said pressure wheel is applied, means carried by said frame for moistening the gummed side of said tape before it is applied to said surface, a handle for said frame whereby said pressure wheel is manually rolled along said surface, and a blade carried movably by said frame and operable by the movement of said handle toward the surface to which tape is being applied to cut said tape at any desired length.

8. A gummed tape comprising a frame adapted to carry a roll of gummed tape, a pressure wheel rotatably carried by said frame whereby tape drawn from said roll is applied under pressure to

any surface on which said pressure wheel is rolled, means carried by said frame for moistening the gummed side of said tape before it is applied to said surface, a handle for said frame whereby said pressure wheel is manually rolled along said surface, a cutting blade pivotally carried by said frame adjacent the lower edge thereof and adapted for movement toward the tape as it moved around said pressure wheel, whereby when 5 said handle is moved toward the surface to which tape is being applied, the back of said blade is moved into contact with said surface, and the cutting edge of said blade is forced into contact with said tape on said pressure wheel, cutting it 10 off at any desired length.

9. A gummed tape applier comprising a frame adapted to carry a roll of gummed tape, a pressure wheel rotatably carried by said frame, a resilient tire carried by said wheel whereby tape drawn 15 from said roll is applied under pressure to any surface on which said pressure wheel is rolled, a moistening roller of resilient absorbent material rotatably carried by said frame engaging said tire and adapted to be driven thereby, whereby the 20 gummed side of said tape is moistened, a handle member removably secured to said frame, said handle member comprising a water reservoir having a sealable filling opening and a cup portion extending beneath and partially encircling 25 said moistening roller, a resilient porous pad contained in said cup and formed to contact said moistening roller about a portion of its periphery, said pad receiving water from said reservoir through an opening provided in the wall of said 30 reservoir adjacent said pad, and a cutting blade 35 pivotally carried at the lower edge of said frame and adapted to be moved into contact with said tape as it passes around said pressure wheel, whereby when said handle is manually moved 40 toward the surface to which the tape is being applied, the back of said blade is moved into contact with said surface, and said blade is forced into contact with said tape, cutting it off at any desired length.
